United States Patent Office.

LEONARD EGLESTON, OF SENECA FALLS, NEW YORK, ASSIGNOR TO RUMSEY & CO., OF SAME PLACE.

Design No. 4,585, dated January 17, 1871.

DESIGN FOR A PUMP.

The Schedule referred to in these Letters Patent and making part of the same.

To all whom it may concern:

Be it known that I, LEONARD EGLESTON, of the village of Seneca Falls, in the county of Seneca and State of New York, have invented or produced a new and original Design for Pump; and I do hereby declare that the following is a full and exact description of the same.

The pump is made of cast-iron or other suitable metal, and, except the peculiarity of my design, in the usual form.

The peculiar form of the stock or barrel of the pump, with the square projection that contains the working valves, with the opening through the base for connecting the suction-pipe to the attachment below the square box containing the valves, with air-chamber, piston-rod, bearer, combined, constitute the design which I claim as my original invention, as shown in the accompanying drawings forming a part of this specification, to which reference is made.

Figure 1 is the design of my force-pump, of which—
The portion A A represents the stock or barrel.
B B, the box containing the valves.
C C, base.
E E, attachment.
F F, air-chamber.
G G, piston.
H H, bearer.
I I, water-chamber.
What I claim as new, and my original design and invention, is—
The design for a force-pump, as shown and described.

LEONARD EGLESTON.
